UNITED STATES PATENT OFFICE.

AUGUSTUS P. MITCHELL, OF ST. PAUL, MINNESOTA, ASSIGNOR OF ONE-HALF TO JAMES E. MCELROY AND RICHARD L. CRESKY, BOTH OF CHICAGO, ILLINOIS.

CAR-AXLE LUBRICATOR.

SPECIFICATION forming part of Letters Patent No. 461,151, dated October 18, 1891.

Application filed January 19, 1891. Serial No. 378,207. (No model.)

To all whom it may concern:

Be it known that I, AUGUSTUS P. MITCHELL, a citizen of the United States, residing at St. Paul, in the county of Ramsey and State of Minnesota, have invented certain new and useful Improvements in Railway-Car-Axle Lubricators, of which the following is a specification, reference being had to the accompanying drawings, which are made a part hereof, and in which—

Figure 1 is a vertical section of one of the improved lubricators applied to a railway-car axle, the latter and the journal-box being shown in transverse section. Fig. 2 is a vertical section of one of the improved lubricators of slightly-modified construction applied to a railway-car-axle, the latter being shown in side elevation and the journal-box in longitudinal section. Fig. 3 is a plan view of the under side of the journal-bearing. Fig. 4 is a side elevation of a train of railway-cars (in outline) equipped with the improved lubricators. Fig. 5 is a plan view of the trucks of a railway-car equipped with the improved lubricator in connection with an air-brake system.

The object of the present invention is to dispense with the use of waste in lubricating car-axles and to provide a lubricator under the absolute control of the engineer, by which oil can at any time be projected onto the journals, so as to thoroughly lubricate them.

A further object of the invention is to enable the engineer or other attendant to thus lubricate all the journals of an entire railway-train or other system at one operation by the use of fluid under pressure conducted to the several lubricators of the system through suitably-arranged pipes.

40 A further object of the invention is to utilize the air-brake system of a railway-train for operating all the lubricators of the train.

To these ends the invention consists of certain features of novelty, that are particularly 45 pointed out in the claims hereinafter.

Referring to the drawings, A represents the journal, B the journal-bearing, C the journal-bearing key, and D the journal-box, all of which may be of any desired construction. Se- 50 cured upon the top of the journal-box is an oil-

cup E, from the bottom of which a drip-pipe e projects downward through the top of the box, through the key, and into an elongated opening b, cut through the bearing near its outer end. With the top of this oil-cup communicates a supply-pipe F, which has the necessary bends and joints and communicates with one of the horizontal branches g of a T G, the vertical branch g' of which is screwed into the bottom of the journal-box, so as to communicate with the interior thereof. In this T is a valve H, which seats outward against a seat formed for it in or at the inner extremity of the vertical branch g'. Normally this valve is held off of its seat by gravity, (or a spring,) so that oil poured into the journal-box may flow freely into and fill the T and the adjacent portions of the pipes communicating therewith; but when fluid under pressure is admitted to the pipe I, which connects with the second horizontal branch g² of the T, the upward pressure upon the valve causes it to seat, thereby cutting off communication between the branch g' and the lower part of the journal-box and compelling the oil to flow 75 through pipe F into oil-cup E, whence it escapes through drip-pipe e onto the top side of the journal. The opening b of the journal-bearing is elongated, so that its lateral movement will not be interfered with, and its under or wearing face is provided with grooves b', through which the oil travels and reaches 80 all parts of the journal. The vertical branch g' of the T projects slightly above the bottom of the box, so that grit and other foreign substances that sink to the bottom will not enter it and be carried up to the journal.

The form of the invention shown in Fig. 2 differs from that shown in Fig. 1 only in that, instead of the T of the form shown in Fig. 1, 90 the form shown in Fig. 2 has a simple box J, situated in the journal-box and secured to the bottom thereof beneath the journal. This box has in its top an opening j, and surrounding this opening is a hopper j' for catching 95 the oil as it drips from the journal and directing it into the box. The T of Fig. 1 and the box J of Fig. 2 are, however, equivalents, in that they are both receptacles having openings for receiving the oil that drips from the 100

journal; and, furthermore, they have equivalent accessories—namely, a valve for closing said opening, a pipe for admitting fluid under pressure, and a pipe for conveying oil therefrom to the journal to be lubricated. In Fig. 2 the hinged valve H' closes the opening *j* the instant fluid under pressure is admitted to the box J, and the results that follow are precisely the same as those that follow the closing of branch *g'* by valve H.

For many reasons the fluid which I prefer to use for expelling the oil from the receptacle X is air; but if the circumstances of any particular case should make water, steam, or any other fluid preferable such other fluid may of course be used and the results will be satisfactory. It is obvious, also, that the source whence this fluid under pressure is derived and the particular arrangement of the pipes for conveying it to the several lubricators of a system are matters which may be left to convenience and the exigencies of particular cases. In Fig. 4 I have shown a railway-train equipped with the improved lubricators, the fluid-pressure pipe I of each lubricator being connected with a supply-pipe K beneath each car, the pipes K of the several cars being coupled together by detachable couplings, similar in construction to those used for coupling the train-pipes of an air-brake system. The forward end of the system of pipes K communicates with a pressure-fluid reservoir L, which may be kept supplied with fluid under pressure in any suitable manner. A valve M, placed in the pipe K within convenient reach of the engineer, enables him to admit a supply of pressure-fluid to the train-pipe at any time, and thereby throw oil onto the tops of the journals in the manner already described. Or, instead of having a separate system of pipes, &c., for supplying the lubricators with fluid-pressure, the customary air-brake system may be tapped at any convenient place and the pipes I suitably connected thereto. In Fig. 5 I have shown the air-brake system tapped between the auxiliary reservoir N and the brake-cylinder O, and a pipe P communicating therewith and having suitable branches, with which the pipes I communicate. By this means each time air is admitted to the brake-cylinder for applying the brakes it is also admitted to the lubricators and a supply of oil forced up to the oil-cups E in the manner already described. Less pressure is of course required for operating the lubricators than for operating the brakes, and in order to avoid an injurious excess of pressure in the lubricator system the pipe P may be provided with a needle-valve for regulating its capacity, or the same result may be obtained by employing a pipe having a bore of just the necessary capacity.

I have shown and described my improved lubricator system as applied to a train of railway-cars; but it is obvious that it may be applied to any system of journals requiring lubrication.

Having thus described my invention, the following is what I claim as new therein and desire to secure by Letters Patent:

1. In a lubricator, the combination, with a receptacle for receiving the oil that drips from the journal, of a source of fluid-pressure, a pipe leading therefrom and communicating with said oil-receptacle, whereby fluid under pressure may be admitted to said receptacle for expelling the oil therefrom, and a second pipe communicating with said receptacle for conveying the oil to the journal, substantially as set forth. 70

2. In a lubricator, the combination, with a receptacle having an opening for receiving the oil that drips from the journal, of a valve for closing said opening, a source of fluid-pressure, a pipe leading therefrom and communicating with said oil-receptacle, whereby fluid under pressure may be admitted to said receptacle for expelling the oil therefrom, and a second pipe communicating with said receptacle for conveying the oil to the journal, 85 substantially as set forth. 90

3. In a lubricator, the combination, with a receptacle having an opening for receiving the oil that drips from the journal, of a valve for closing said opening, an oil-cup situated above the journal and having a drip-pipe leading thereto, a pipe communicating with said receptacle and discharging into the oil-cup, and a source of fluid-pressure also communicating with the receptacle, substantially 95 as set forth. 100

4. The combination, with the journal and the journal-bearing having grooves in its under surface for distributing the oil over the entire surface of the journal, of a receptacle 105 having an opening for receiving the oil that drips from the journal, a pipe communicating with said receptacle and extending above the journal-bearing, a source of fluid-pressure, and a second pipe leading therefrom and communicating with said receptacle, the journal-bearing being provided with an opening 110 for the passage of oil to the journal, substantially as set forth.

5. The combination, with a plurality of 115 journals, of a lubricator applied to each, each of said lubricators having a receptacle for receiving the oil that drips from the journal, and a pipe communicating with said receptacle for conveying the oil back to the journal, a source of fluid-pressure, pipes leading therefrom and communicating with the oil-receptacles of all of said lubricators, and a valve for controlling the supply of fluid-pressure to said receptacles, substantially as set 120 forth. 125

6. The combination, with a railway-car, of receptacles for receiving the oil that drips from the journals, pipes communicating with said receptacles for conveying the oil back to the journals, a source of fluid-pressure, pipes extending along the car and communicating with all of said receptacles for supplying them with fluid-pressure, and a valve whereby the 130

admission of said fluid-pressure to said receptacles is controlled, substantially as set forth.

7. The combination, with a railway-car and an air-brake apparatus applied thereto, of receptacles for receiving the oil that drips from the journals, pipes communicating with said receptacles for conveying the oil back to the journals, and a second set of pipes communi-

cating with said receptacles and with the air-brake system, whereby fluid-pressure may be admitted to said receptacles for expelling the oil therefrom and flooding the journals, substantially as set forth.

AUGUSTUS P. MITCHELL.
